UNITED STATES PATENT OFFICE.

JAMES F. GUTHRIE, OF SOMERVILLE, MASSACHUSETTS.

IMPROVEMENT IN EJECTOR-CONDENSERS.

Specification forming part of Letters Patent No. 178,434, dated June 6, 1876; application filed February 17, 1876.

To all whom it may concern:

Be it known that I, JAMES F. GUTHRIE, of Somerville, in the county of Middlesex and State of Massachusetts, have invented a new and useful Improvement in Ejector-Condensers, of which the following is a specification:

This invention relates to ejector-condensers, which are used to condense the exhaust steam from steam-engines, and entirely dispense with the air-pump; and the invention consists of a peculiar construction and combination of parts, which will be fully hereinafter described, and specifically pointed out in the claim.

In the accompanying plate of drawings, Figure 1 represents a vertical cross-section of an ejector-condenser having my improvements attached thereto; Fig. 2, a horizontal cross-section on line *x x*, Fig. 1; and Fig. 3 is a horizontal cross-section of the water-conduction tube on line *y y*, Fig. 1.

A in the drawings represents an ejector-condenser, of which B is the inlet for steam; C, the inlet for water; D, the discharge-pipe, and E the induction-tube; and F, the conduction-tube for the passage of the water after it has entered at inlet C to the combining-chamber G; H, the plug in conduction-tube F, to regulate the flow or quantity of water, all as ordinarily in ejector-condensers now in use, and therefore needing no further description herein. I is the discharge-nozzle of conduction-tube F. This discharge-nozzle I is formed substantially as shown, and is adapted by a screw-thread, *a*, to be screwed on or off of conduction-tube F.

When the steam in the running of the engine is of a high pressure at the point of exhaust, for a complete and effective action of the water upon the steam in the working of the condenser, a larger surface of water must be exposed in the combining-chamber for contact with the steam, and, obviously, when the steam is at a lower pressure at the exhaust-point, a corresponding decrease of the surface of the water is necessary.

The discharge-nozzle I, in its position as shown in the drawing, is adjusted for a high pressure of steam at the exhaust-point, exposing to the steam a greater surface of the column of water passing through the condenser, as the end *b* of discharge-nozzle I is at a greater distance from the bottom of combining-chamber, and when the steam at the exhaust-point is at a low pressure, by un-

screwing the discharge-nozzle accordingly as the steam is more or less of a lower pressure at the exhaust-point, the discharge-nozzle can be adjusted to the requirements of the ejector-condenser, as is obvious.

L, an opening or hand-hole in the casing at *d* of the condenser, and covered by the cap M, which is adapted to be readily removed when desired.

To adjust the discharge-nozzle I to its proper work through the opening or hand-hole, a rod or wire can be inserted into one of the holes, *c*, in the periphery of discharge-nozzle I, which can then be easily turned to its proper adjustment.

By the use of this hand-hole L, the breaking of joints of the condenser is avoided, and the discharge-nozzle can be adjusted without interfering with its operation or the running of the engine.

In adjusting the discharge-nozzle I to the pressure of steam at the exhaust-point, the plug H is also accordingly regulated to maintain the same quantity of water passing through discharge-nozzle.

N is a stuffing-box, to prevent leakage of steam or water through the joint *a* of discharge-nozzle I and conduction-tube F, which would interfere with the working of the condenser.

This improvement is applicable to condensers for steam-pumps, and also as well to injectors of boilers; but when used in injectors, the pipes connecting with the injector must be arranged so that the steam will enter inlet C, and the water inlet B.

I am aware of the patent to Robinson and Gresham, dated May 29, 1866, and I disclaim the construction therein shown.

Having now described my invention, what I claim, and desire to secure by Letters Patent, is—

In an ejector-condenser, having the hand-opening L and conductor-tube F, the adjustable discharge-nozzle I, having the recesses *c*, by which it is adjusted through the hand-opening L, substantially as described.

The above specification of my invention signed by me this 31st day of January, A. D. 1876.

JAMES F. GUTHRIE.
